UNITED STATES PATENT OFFICE.

BENJAMIN F. CURTIS, OF COVINGTON, KENTUCKY.

HOLDING MEANS FOR ATTACHMENTS FOR SEWING-MACHINES.

1,072,581.

Specification of Letters Patent. Patented Sept. 9, 1913.

Application filed December 30, 1910. Serial No. 600,133.

To all whom it may concern:

Be it known that I, BENJAMIN F. CURTIS, a citizen of the United States, residing at Covington, in the county of Kenton and 5 State of Kentucky, have invented certain new and useful Improvements in Holding Means for Attachments for Sewing-Machines, of which the following is a specification.

10 My invention relates to holding means for attachments for sewing machines.

The object of my invention is to provide means on attachments for sewing machines, such as seam-binders, hemmers and the like 15 for holding said attachments steady and prevent them from sliding and coming into contact with the presser-foot as they so often do now.

My invention is shown mounted upon a 20 seam-binder attachment, this particular attachment being used to a great extent in factories making garments.

It has been found that the set-screw or thumb-screw which has been provided to 25 secure the seam-binder or attachment to the bed-plate of the sewing machine has been insufficient to hold the seam binder properly, inasmuch as the constant vibration of the machine in operation causes it to work 30 loose and also the operator very often engages or strikes the end of the seam binder and works same loose, allowing it to swing using the thumb-screw as a pivot and invariably bringing the end of the seam 35 binder into contact with the bifurcated presser-foot. This is done so often that the end of the seam binder becomes dilapidated and worn out.

On account of the vast number of seam 40 binder attachments used in factories manufacturing garments, and owing to the carelessness of the operators, firms require their employees to furnish their own seam-binder attachments, the expense being too great to 45 justify them in furnishing said attachments. Thus it is seen that great advantage is derived from my device, which may be readily attached to seam-binders, said device being inexpensive to manufacture, simple in construction, and durable in use.

By placing my improved holding device upon the attachment the life of said attachment is prolonged indefinitely, and will 50 absolutely prevent the end of the seam binder from engaging the presser-foot and

will always be held in proper position to turn out the work properly.

Very often the seam-binder attachments are thrown out of alinement due to the loosening of the thumb-screw and thereby 60 cause the seam to be irregular. My invention, however, insures a uniform seam to be produced at all times, and absolutely holds the attachment firmly in position.

In the accompanying drawing which 65 serves to illustrate my invention: Figure 1 is a perspective view of a fragment of the base plate of a sewing machine having a seam binding attachment which is equipped with my invention. Fig. 2 is a 70 detail view of my holding device which is adapted to be mounted upon the attachment. Fig. 3 is a fragmentary view of the base plate of a sewing machine showing where the devices are adapted to be placed 75 and fastened. Fig. 4 is a plan view of a seam binding attachment equipped with my device, the attachment being shown mounted upon a fragment of the base plate of a sewing machine. Fig. 5 is a side elevation of a seam-binder attachment equipped with my invention. Fig. 6 is a side elevation 80 showing a modification, and Fig. 7 is an end elevation of the seam binder.

Referring more particularly to the drawing, 85 Fig. 1 illustrates the bed plate of a sewing machine upon which is mounted a needle plate 2 and a slide plate 3 in the end thereof. A presser-foot 4 is provided and is mounted in the usual manner upon the 90 standard 5 in which is mounted the reciprocating socket 6 carrying the needle 7.

In nearly all of the feed cover plates 2 a hole 8 is provided for the purpose of securing some special attachment to the machine. 95 Taps 9 are provided in the bed plate 1 for receiving a thumb-screw 10, which is intended to hold the seam binder attachment 11.

The seam-binder 11 is of the usual construction having a guide and support flange 100 12 thereon and a hollow curved neck 13 in which the seam-binding strip passes. The straight end of the hollow neck of the seam binder tapers or converges, the inner edges 105 of which turn under to form the seam binding strip of material in the proper shape for binding the garment desired, as shown in Fig. 6.

An arm 14 having a slot 15 therein is provided on said seam-binder 11 and is adapted 110

to extend over the holes 9 in the bed-plate 1 of the sewing machine. The thumb-screw 10 is adapted to pass through the slot 15 into one of the holes 9 and to clamp said extension 14 to the bed plate of the sewing machine, and is thus supposed to hold the seam-binder in proper position. The inefficiency of this device has been mentioned, and I therefore provide an arm 17, which is adapted to be riveted on the extension 14 of the seam-binder 11. The arm 17 is provided with a downwardly extending portion 17^a which is provided with a point. It is the downwardly extending portion 17^a which is adapted to enter the hole 8 in the feed cover plate 2. The outer end of the arm 17 may be bent if necessary to cause the downwardly extending portion to properly engage the hole 8. Thus the arm 17 being firmly fastened to the seam-binder 11 and accurately engaging the hole 8 in the cover plate, it is readily seen that in combination with the thumb screw holding device 10 that the seam-binder will be firmly held in position, and cannot possibly swing to right or left.

It will be understood that if the hole 8 is not in proper position or if no hole is provided, a hole may be drilled in the plate 2 at the proper position.

My device serves as a guide for placing the attachment in accurate position for use, and maintains it in such position after it is so placed and clamped by the thumb-screw 10, thus affording an accurate guide for insuring absolutely the proper and accurate position of the attachment for use.

The cheapness of my invention and the

simplicity of same enables it to be placed on the seam-binder at very little cost, and its usefulness is invaluable to operators of machines upon which seam-binders are used to any great extent.

Modifications of my invention may be made, such as changing the shape of the particular holding device and fastening it at a different point upon the attachment, and I do not wish to be confined to the exact details shown.

If desired, my device may be made adjustable by providing a boss 18 on the seam-binder 11 and providing same with a slot 19 which the arm or holding device 17 may enter. The boss then may be provided with a set-screw 20 which bears against the holding device 17 and clamps it to said attachment. In this manner the holding device may be adjusted to any position.

What I claim as new and desire to secure by Letters Patent is:

In a seam-binder attachment for sewing machines having a slotted arm thereon provided with a set-screw extending through said slotted arm and adapted to clamp said arm to the bed-plate of a sewing machine, a rigid arm riveted on said seam binder attachment at right angles to said slotted arm, and a turned down portion at the end of said rigid arm adapted to enter a hole in the bed plate of a sewing machine and prevent movement of said attachment, substantially as set forth and for the purposes specified.

BENJAMIN F. CURTIS.
